UNITED STATES PATENT OFFICE.

CARL E. MATSON, OF CHICAGO, ILLINOIS.

WINDOW DEVICE.

Application filed October 22, 1925. Serial No. 64,214.

This invention aims to provide a window, the sashes of which may be opened, without removing the screen from the window frame, and without causing the sashes to project inwardly into the apartment. Another object of the invention is to provide novel means whereby access may be had readily to both sides of each sash, to wash the glass in the sashes.

10 It is within the province of the disclosure to improve generally and to enhance the utility of devices of that type to which the invention appertains.

15 With the above and other objects in view which will appear as the description proceeds, the invention resides in the combination and arrangement of parts and in the details of construction hereinafter described and claimed, it being understood that changes 20 in the precise embodiment of the invention herein disclosed, may be made within the scope of what is claimed, without departing from the spirit of the invention.

In the drawings:—

25 Figure 1 shows in elevation, a device constructed in accordance with the invention, parts being in section; Figure 2 is a section on the line 2—2 of Figure 1, the sashes being closed; Figure 3 is a section on the line 2—2 of Figure 1, the sashes being open; Figure 4 is a section on the line 4—4 of Figure 1; Figure 5 is an elevation showing one of the tracks; Figure 6 is a detail enlarged from Figure 4; Figure 7 is a sectional view showing the lower 35 track and attendant parts.

The numeral 1 marks a frame comprising uprights 2, a lintel 3 and a sill 4. The sill 4 carries an inverted trough-shaped track 5, and there is a trough-shaped track 6 on the 40 lintel 3.

A first sash 7 is provided and is mounted for right-line reciprocation in the direction of the arrow A in Figure 3. On its lower edge, the first sash 7 has upstanding brackets 8 engaged with the depending flange of the track 5. On its upper edge, the first sash 7 has depending brackets 9 engaged slidably with the upstanding flange of the track 6. There are openings 10 in the said flanges of 50 the tracks 5 and 6, so that when the first sash 7 is pushed to the right in Figure 3, in the direction of the arrow A, as far as the sash can go, the sash 7 then may be detached, in the direction of the arrow B in Figure 3, the 55 ends of the brackets 8 and 9 passing outwardly through the openings 10.

The numeral 12 designates a second sash which has a compound movement in the direction of the arrow A of Figure 3 and in the direction of the arrow B. The sashes 12 and 60 7 are beveled on their inner vertical edges, as at 14, to facilitate the relative movement of the sashes in the direction of the arrow B, the sashes being in the same plane, when they are in closed position. The sashes 12 and 65 7 are held in the same plane, and in a closed position, by a latch mechanism 15, of any desired sort, on the inner portions of the said sashes.

The second sash 12 is adapted to slide in the 70 direction of the arrow B on a wear strip 16 seated in the sill 4. The wear strip 16 is inclined toward the outer edge of the frame 1. The lintel 3 and the sill 4 are supplied with outwardly inclined guides 17 having slots 18 75 receiving pins or other projections 19 carried by wear strips 20 on the upper and lower edges of the sash 7, the said wear strips 20 being adapted to cooperate with the guides 17. On its lower portion, the sash 12 is provided 80 with a horizontally swinging latch 24 adapted to cooperate with a keeper 25 on the sill 4.

A screen 21 is secured in any desired way to the outer surface of the frame 1. If desired, the screen 21 may be hinged at 22 to one 85 of the uprights 2, and may be held closed by a hook and eye connection 23 on the screen and on the sill 4—although it will be understood that the screen may be constructed and mounted as desired.

90 In practical operation, the sash 12 is slid in the direction of the arrow B in Figure 3 until it is clear of the sash 7, the projections 19 on the sash 12 sliding outwardly in the slots 18 of the guides 17. The first sash 7, then, 95 may be slid to the right, into the position shown in Figure 3, behind the sash 12, the latch 24 and the keeper 25 retaining the sash 12 in the position shown in Figure 3, the sash 7 abutting against the pivotal mounting of the 100 latch 24, as indicated in Figure 3, to prevent the first sash 7 from being slid any further to the right. Referring to Figure 3, it will be observed that there is ample space between the outer edges of the sash 7 and of the sash 12, and the uprights 2, so that air can enter. It is to be observed that, in the opening of the sashes 7 and 12, it has not been necessary to remove the screen 21: nor when the sashes are 105 in the position shown in Figure 3, do they 110 project inwardly into the apartment.

When it is desired to wash the panes of the

sashes 7 and 12 the screen 21 may be opened or removed. Then the sash 12 may be swung outwardly on its pivot elements 19 until the sash stands about at right angles to the sash 7. It will then be possible for an operator to have access to both sides of the sash 12, and to both sides of the sash 7, for the purpose of washing the panes.

Although the device has been shown as embodying two sashes, it may consist of one sash, or more than two sashes.

What is claimed is:—

In a device of the class described, a frame, a first sash, means for mounting the first sash for right-line sliding movement on the frame, a second sash aligned with the first sash, means for mounting the second sash on

the frame for movement in a direction transverse to the direction in which the first sash slides, for movement in a direction parallel to the direction in which the first sash slides, and for swinging movement about at right angles to the first sash, and a latch mechanism forming a releasable connection between the second sash and the frame, to limit all of the aforesaid movements of the second sash, the latch mechanism being interposed in the path of the first sash to stop the right-line sliding movement of the first sash when the first sash moves toward open position. 25

In testimony that I claim the foregoing as my own, I have hereto affixed my signature. 30

CARL E. MATSON.
